UNITED STATES PATENT OFFICE.

JOSEPH T. JARET, OF BROOKLYN, NEW YORK.

DESIGN FOR A DESK LAMP.

Application filed May 10, 1929. Serial No. 31,162. Term of patent 3½ years.

To all whom it may concern:

Be it known that I, JOSEPH T. JARET, a citizen of the United States, residing at 3202 Ave. D, Brooklyn, in the county of Kings and State of New York, have invented a new, original, and ornamental Design for a Desk Lamp, of which the following is a specification, reference being had to the accompanying drawing, forming a part thereof.

The figure is a perspective elevation view of a desk lamp showing my new design.

I claim:

The ornamental design for a desk lamp, as shown.

JOSEPH T. JARET.
